Patented Dec. 6, 1921.

UNITED STATES PATENT OFFICE.

JACOB P. WRIGHT, OF BARBERTON, OHIO, ASSIGNOR TO THE DIAMOND MATCH COMPANY, OF CHICAGO, ILLINOIS, A CORPORATION OF ILLINOIS.

BOX-FILLING MACHINE.

1,399,039.

Specification of Letters Patent.

Patented Dec. 6, 1921.

Application filed April 4, 1921. Serial No. 458,255.

To all whom it may concern:

Be it known that I, JACOB P. WRIGHT, a citizen of the United States, and resident of Barberton, in the county of Summit and 5 State of Ohio, have invented certain new and useful Improvements in Box-Filling Machines, of which the following is a specification.

This invention relates to box filling machines, having reference especially to certain improvements in the box-tray filling mechanism illustrated in Letters Patent of the United States No. 1,300,763, dated April 15, 1919.

15 In the patented mechanism a conveyer for a succession of box-trays is mounted to travel under the slotted lower delivery portion of a longitudinally reciprocative inclined hopper containing matches (or splints) to be 20 supplied to the trays in measured quantities. This conveyer is provided with spaced-apart tray-holding blades which extend above the tops of the trays embraced thereby, and which blades, as the conveyer progresses, gradually enter the interior of the 25 hopper in a manner to receive quantities of matches between adjacent blades and transfer the matches thence to the trays. An inclined yielding guard structure is arranged 30 to lie within the lower portion of the hopper and overhang the adjacent blades of the conveyer in such wise as to provide a throat member which is designed to gage and limit the level of the matches between the blade 35 extensions preparatory to the delivery of the matches to the underlying trays, all as fully set forth in Patent No. 1,300,763 aforesaid.

In the practical operation of the patented 40 mechanism, particularly when the machine is running at relatively high speed, the matches at the lower end of the hopper have a tendency to compact within the space between the bottom of the hopper and the overhanging guard structure in such a manner as not only to impose considerable restraint 45 on the advancing blades, but also to force the guard structure unduly upward, thereby disturbing the parallelism of the matches 50 and also impairing the accurate measurement of the quantities thereof to be delivered to the trays.

The object of my invention is to provide 55 a simple and efficient construction which will overcome the objection above mentioned;

and to that end I provide at the lower end of the hopper a novel cut-off device which automatically defines the level of the matches between the blades and at the same time contacts with the body of the guard structure 60 to deflect the surplus matches upward and backward and thereby reduce the resistance of the matches to the advancing blades, as will be hereinafter described and claimed.

In the drawings—

Figure 1 is a longitudinal vertical section, partly in elevation, of the delivery end of a match-feeding hopper embodying my invention, showing a part of the tray conveyer as supplied with trays and the selecting action 70 upon the matches of the upward extensions of the tray-holding members of the conveyer.

Fig. 2 is a plan of the lower or delivery end of the hopper, and adjuncts.

Fig. 3 is a transverse section through the hopper and conveyer, on the line 3—3 of Fig. 1.

Fig. 4 is a perspective view of a portion of the guard structure, showing the cut-off 80 device at the lower end thereof.

Referring to the drawings, 10 designates an elongated inclined hopper to the upper end of which matches are delivered from a suitable source of supply so as to lie in parallelism within and transversely of the hopper. This hopper comprises an inclined bottom 11 having two parallel sides 12 spaced apart slightly greater than the length of a match. The lower ends of the hopper are 90 horizontally extended, as at 13, and their outer ends are connected by a transverse end plate 14 which is appropriately recessed in its lower edge, as at 15, for the free passage of the reduced upper extensions 16 of 95 upstanding tray-holding blades 17 on a continuously movable endless conveyer 18. The side extensions and the adjacent part of the bottom overhang a horizontal bed or table 19. The hopper is provided with a suitably disposed slide 20 which is mounted on a guide 21 on the table, so as to permit longitudinal vibration of the hopper. This slide is formed on a bracket 20' fixed to the hopper. The hopper is also provided with depending lugs 22 which embrace an eccentric 100 23 carried by a shaft 24 which is driven in any suitable manner, so as to effect the rapid bodily vibration of the hopper longitudinally and thus insure the feeding of the 110

matches therealong from its upper to its lower or discharging end.

The lower end of the bottom of the hopper is provided with a longitudinal slot 5 25 for the free passage into and from the hopper of the extensions 16 of the conveyer blades. This slot is of less width than the length of a match and hence, while the matches in the adjacent part of the hopper 10 are supported at their ends, access through the opening can be had to the matches by the progressing blade extensions of the conveyer as the latter passes about its guide wheel 26 to a horizontal position longitudinally of the hopper. In such travel of the conveyer the reduced upper extensions 16 of the blades 17 successively enter the slotted portion 25 of the hopper bottom and separate approximately measured quantities of matches from the opposing mass; thence as the conveyer progresses the blades stand upright and advance the thus gathered matches along the slotted portion of the bottom and deliver them to the underlying trays, all as described in Patent No. 20 1,300,763 aforesaid.

27 designates the guard structure which is arranged to lie within the lower portion of the hopper and overhang the adjacent up-standing blades of the tray conveyer. This structure comprises an inclined metal strip which is secured at its upper end to the bracket 20' of the hopper. The lower portion of the strip is curved downward, as at 30 28, and extended horizontally, as at 29, such extension being directly above the outer extremity of the slotted hopper bottom, as seen in Fig. 1. To the underside of the extension is secured a horizontal plate 30, 40 termed a cut-off plate, one end of which is extended beyond the curved portion of the strip so as to provide a tongue or shelf 31 spaced below the body of the strip and lying in close parallel relation to the tops of the progressing blade extensions. This tongue is beveled upwardly from its free end similarly to a wedge, and the undersurface of the plate is preferably transversely toothed or serrated, as at 32. Such undersurface is 45 positioned in proximity to the path of the upper edges of the blade extensions and is of sufficient length to span two adjacent extensions during their travel thereunder. A backer-piece 33 fixed between the walls of 50 the hopper lies in close relation to the guard extension 29 and thus prevents upward movement of the latter and the cut-off plate 30.

From the foregoing described construction 60 it will be seen that as the blade extensions, with their contained matches, pass under the beveled end of the plate 30, such end acts to raise the mass of matches which is above the level of the blade extensions, 65 thus performing the function of a cut-off

member to insure a constant level of the matches confined between adjacent blade extensions when such extensions have passed beneath the plate 30. It will also be seen that as the cut-off plate is vibrated 70 longitudinally concurrently with the guard structure and the hopper, the matches thus raised and separated by the beveled end of the plate are forced against the curved portion 75 28 of the structure and that such portion deflects them back against the inclined under side of the structure, thus effecting a continuous return motion or "circulation" of the surplus matches as the conveyer advances, and thereby obviating all liability 80 of the crowding of the matches against and in opposition to the motion of the conveyer blades.

As each box-tray passes beyond the slotted end of the hopper, the measured 85 quantity of matches positioned between a pair of blade extensions, falls into the underlying tray, the initial descent and distribution of the matches being contributed to by the action of the serrated surface of 90 the vibrating cut-off plate on the contiguous matches.

34 designates a vibratory rod which is mounted to extend longitudinally of and overhang the hopper in a manner to bear 95 yieldingly upon the mass of matches during their descent, as described in Patent No. 1,300,763 aforesaid.

It is to be understood that I do not limit my invention to the particular details of 100 construction herein disclosed, as the parts may be modified within the principle of the invention and the scope of the appended claims.

I claim—

1. In a box-filling machine, the combination with a splint feeding hopper, of a tray-conveyer mounted to travel under the delivery portion of the hopper and having spaced tray-holding members provided with up-standing measuring portions adapted to enter the interior of the hopper and transfer splints therefrom to the trays on the conveyer, and a cut-off member mounted adjacent the delivery end of the hopper and having a tongue extending in close parallel relation to the top of the said measuring portions as they progress to the delivery end of the hopper.

2. In a box-filling machine, the combination with a splint feeding hopper, of a tray-conveyer mounted to travel under the delivery portion of the hopper and having spaced tray-holding members provided with up-standing measuring portions adapted to 120 enter the interior of the hopper and transfer splints therefrom to the trays on the conveyer, and a cut-off member mounted adjacent the delivery end of the hopper and having a tongue extending in close parallel 125 130

relation to the top of the said measuring portions as they progress to the delivery end of the hopper, said tongue being beveled upward from its free end.

- 5 3. In a box-filling machine, the combination with a splint feeding hopper, of a tray-conveyer mounted to travel under the delivery portion of the hopper and having spaced tray-holding members provided with 10 up-standing measuring portions adapted to enter the interior of the hopper and transfer splints therefrom to the trays on the conveyer, a cut-off member mounted adjacent the delivery end of the hopper and having 15 a tongue extending in close parallel relation to the top of said measuring portions as they progress to the delivery end of the hopper, the under surface of said member being serrated, and the free end of the 20 tongue being beveled, and means for longitudinally vibrating said hopper.
4. In a box-filling machine, the combination with an elongated splint-feeding hopper, of a tray-conveyer mounted to travel 25 under the delivery portion of the hopper, said conveyer having spaced tray-holding members which project above the tops of the adjacent trays, and an inclined guard structure arranged to overhang the conveyer 30 in proximity to the path of said members as they approach the delivery portion of

the hopper the lower end of said structure comprising a cut-off member having a tongue which underhangs the body of the structure and extends in close parallel relation to the top of the tray-holding members of the conveyer. 35

5. In a box-filling machine, the combination with an elongated splint-feeding hopper, of a tray-conveyer mounted to travel 40 under the delivery portion of the hopper, said conveyer having spaced tray-holding members which project above the tops of the adjacent trays, an inclined guard structure arranged to overhang the conveyer in proximity to the path of said members as they approach the delivery portion of the hopper, the lower end of said structure being curved downwardly and including a cut-off member which extends below and beyond the 45 curved portion of the structure and in close parallel relation to the top of the tray-holding members of the conveyer, said cut-off member being beveled upward from its free end toward the curved portion of the 50 guard structure, and means for longitudinally vibrating said hopper. 55

Signed at Barberton, in the county of Summit and State of Ohio, this 31st day of March, A. D. 1921.

JACOB P. WRIGHT.
